Specification for Design.

Patented Sept. 22, 1914.

Application filed August 1, 1914. Serial No. 854,578. Term of patent 14 years.

To all whom it may concern:

Be it known that we, JOHN J. BROWNRIGG, HARRY HENDERSON, and ARTHUR E. CASE, citizens of the United States, residing at Marion, in the county of Grant and State of Indiana, have invented a new, original, and ornamental Design for Portable Electric Lamps, of which the following is a specification, reference being had to the accompanying drawing, forming a part thereof.

The figure is a perspective of a portable electric lamp showing our new design.

The lamp comprises a cylindrical body A

having a conoidal lamp holder B projecting from the upper portion of the body at one side thereof, a handle C at the opposite side thereof and a bail D above the body.

We claim:

The ornamental design for a portable electric lamp, as described and shown.

JOHN J. BROWNRIGG.

HARRY HENDERSON.

ARTHUR E. CASE.
